BOTTLE AND JAR SEAL.

954,897.

Specification of Letters Patent. Patented Apr. 12, 1910.

Application filed September 2, 1908. Serial No. 451,309.

To all whom it may concern:

Be it known that we, LOUIS G. STEININGER and ALTON A. WALRATH, citizens of the United States, residing at Fort Plain and 5 Minden, respectively, in the county of Montgomery and State of New York, have invented certain new and useful Improvements in Bottle and Jar Seals, of which the following is a specification, reference being 10 had therein to the accompanying drawing.

Our invention relates to an improved bottle and jar-seal, and we declare the following is a full, clear, concise and exact description thereof, sufficient to enable one skilled in the 15 art to make and use the same, reference being had to the accompanying drawings in which like characters refer to like parts throughout.

While we call the device a bottle and jar-seal it is also applicable to seal any sort of a receptacle, such as a fruit-jar, crock, case or other vessel wherein the contents are to be sealed against atmospheric actions, or the effect of all tainting or corroding closure 25 members or materials. The advantages of the device are somewhat pointed out herein, the illustrations showing some of its applications.

In the drawings Figure 1 shows it applied 30 to a fruit-jar of familiar style. Fig. 2 is a medial sectional view of the metallic portion of the stopper. Fig. 3 shows the device in place for closing a bottle, a different kind of fastening device being shown, while Fig. 35 4 shows the bottle sealed. Fig. 5 shows a bottle sealed, the metallic spring-like member being of different style, Fig. 6 showing the bottle ready for sealing.

Referring to the figures in detail A represents the vessel to be sealed, on which there 40 will be the ordinary lip or curved edge a , of greater or less extent, as the case may be.

In Fig. 1 the receptacle is an ordinary fruit-jar adapted to receive the fastener in 45 this case the threaded ring B for holding the cover on the jar. The ordinary glass cover B' is used in conjunction therewith, the two making the cap and fastener. In the other figures the fastener is a metallic cap C having 50 its rim c somewhat elastic, the same being provided with inwardly projected teeth c' so formed and placed that the cap, being forced onto the bottle, the teeth will engage the bottle as at a' , at the under edge

of the lip. The fastener in these cases comprises the cap also as part of it. 55

The sealing parts proper consist of a metallic, resilient member D as a disk shown in Figs. 1-4, or a ring shown in Figs. 5 and 6. The outer edge of this member, be it disk, 60 ring or other form, is fashioned as at d with a curved annular channel, to fit on or over the lip surface of the bottle or jar and by pressure thereon yield sufficiently to press against the lip for a considerable extent of 65 surface as seen in the several figures, or at a plurality of points, as in the form of fastener shown in Fig. 1 where the jar has a surface a'' outside of what has been termed the lip and to fit which the seal D, in that 70 case, has its outer edge curved in section, in the annular spring edge d' . From the outer edge, this sealing member is formed to rise toward the center part D', which in the disk form is at the center and in the other form 75 is at the inner edge of the ring. Intermediate the outer edge of this sealing member and the central part it is formed in such lines, in cross-section as will give it the desired resiliency. As seen, the central part of 80 this member, when the closure or fastening devices are secured in place, is pressed upon by such devices and crowded inward which applies a considerable pressure of the sealing member described against the lip of the 85 jar or, vessel, yet a pressure somewhat yielding so as to conform the sealing members to the lip of the vessel in an evenly distributed pressing contact. It is to be noted that the extent of such contacting surface, both on the 90 inside and outside of the lip, or the number of such contacting points is such that, though the lip be chipped at points the sealing contact is effected at other parts of the surface or at other points so that the chipping of the 95 vessel does not interfere with the efficiency of the seal. The other sealing member, by the use of which particularly the seal becomes air-tight, consists of a softer member E, in the form of a disk preferably. This 100 member, or lining of the other seal member as it may be termed, since the two may be secured together, is preferably made of a somewhat spongy material, such as paper, of a proper thickness. It is preferably treated 105 in some suitable way, as by oil or a coating of paraffin, so as to make it proof against the action of the contents of the vessel and

against affecting the contents in any way, unless as a preservative. The outer edge of this member conforms more or less to that of the other sealing member, but its interior 5 portion is substantially plane. It will be seen that this member lies between the lip of the bottle or jar and the metallic seal and that when the parts are properly placed and the closure or fastening members secured in 10 closed position the bottle is tightly sealed from all outer conditions.

The many advantages of the invention, in durability, simplicity and economy, need not be detailed, being shown herewith in one 15 application thereof, and apparent to any one familiar with the requirements and uses of such devices.

Having described our invention, what we claim as new and desire to secure by Letters 20 Patent, is:

1. In a sealing device for a jar having an annular upstanding lip at its mouth surrounded by an outwardly extending concavely curving shoulder the combination of 25 a cap formed to engage the jar, a metallic corrugated resilient member having a curved annular channel adjacent to its periphery and an annular spring edge d' , said annular channel being in approximate conformity 30 with the lip and said spring edge d' in approximate conformity with the surface of the jar outside of the lip and said resilient

member being adapted to be engaged by the cap, and a sealing member E, composed of some yielding substance having its edge in conformity with the lip and outer surface of the jar and adapted to be pressed or forced into an hermetically sealing position by the resilient member. 35

2. In a sealing device, the combination 40 with a jar, having an upstanding lip at its mouth, a sealing disk and a cap having means whereby to secure the same to the jar, of a resilient seal above the disk formed with a series of annular curves extending upwardly and inwardly, the outer edge being formed with a yielding channel portion adapted to spread and to fit closely the lip of the jar, its inner portion being pressed downward and inwardly by the cap when 45 being secured to the jar whereby the resiliency of the seal effects close contact of its edge and the edge of the disk with the lip of the jar across the top of the lip and against the inner and the outer surface 50 thereof, substantially as described. 55

In testimony whereof we affix our signatures in presence of two witnesses.

LOUIS G. STEININGER.
ALTON A. WALRATH.
